REFRIGERATOR CAR STRUCTURE

Victor E. West, New Kensington, Pa., assignor to
 Standard Railway Equipment Manufacturing
 Company, New Kensington, Pa., a corporation
 of Delaware

Application June 10, 1938, Serial No. 213,092

7 Claims. (Cl. 105—404)

The invention relates to refrigerator cars and more particularly to cars having the refrigerator near the roof, commonly called top bunker cars. A refrigerator car is a car having insulated walls, floor and roof and means for cooling the contents of the car during the warm months of the year and for heating the contents during the cold months. In the transportation of many kinds of fresh vegetables, fruits and meats it has been found important that these products be kept within a certain temperature range, depending on the product. If a product becomes too cold it freezes and its market value becomes less; also if it becomes too warm, ripening is hastened and its value decreased because of a shorter storage life.

The essential features of a refrigerator car, in addition to the insulated structure, are means for heating in winter and cooling in summer; provision for the circulation of air from the heating or cooling means to and through the lading, and means to support the lading in the car, usually at a distance above the floor to allow for air circulation between the lading and the floor. 20 The commonly accepted type of refrigerator car is one with ice bunkers positioned adjacent the end walls of the car and separated from the lading compartment by a bulkhead. The air circulates under the bulkhead, up through the lading, and over the bulkhead back to the bunker. This is known as the end bunker car. Another type, known as the top bunker car, has the ice bunkers near the roof from where the air circulates downwardly through flues associated with 25 the walls up through the lading and back to the ice bunkers.

Certain features embodied in this invention apply to any type of refrigerator car, while others obviously apply only to a car having the ice bunkers adjacent the roof.

A number of years ago refrigerator cars were built with a wood framework, wood sheathing, and wood lining and insulated with various materials. Later the framework was made of steel, 45 and only very recently have cars been built with steel sheathing and roof. Designers have been slow to adopt steel for refrigerator cars, partly because of the difficulty of repairing the steel sheathing if it is damaged.

50 Steel sheathed refrigerator cars are commonly built by erecting upon an underframe a steel outer wall or sheathing. Insulation blankets are then applied and the inside lining is secured in place. The ceiling and roof with insulation 55 therebetween are also secured to the outer wall.

If, due to defective construction or to damage during service, it becomes necessary to replace a sheet or post of the wall, it is necessary to practically dismantle the car, removing lining and insulation. It is an object of this invention to construct the inner structure of the car entirely 5 separately from the outer structure. It is then possible to remove and replace sheets of the side or roof without disturbing the insulation. This greatly reduces repair costs and also encourages 10 the construction of steel sheathed refrigerator cars. One of the disadvantages of such cars has been the difficulty of repairing them, but this is now overcome by the construction disclosed here. 15

Another object of the invention is to position flues for the circulation of air between the inner and outer structures. It is a further object to thus maintain the outside width and wall thickness the same and at the same time to increase 20 the inside width of the car.

It is another object of the invention to increase 25 the efficiency of the insulation by constructing and supporting the inner and outer structures separately, thus eliminating the usual connections which are undesirable because they conduct heat from the outside to the inside.

Another object of the invention is to support 30 the lining, ceiling and refrigerant containers directly on the underframe. This not only facilitates repairs to the outer structure, but provides a stronger car and also a lighter car because the outer wall has less load to support and can be made of thinner material.

Another object of the invention is to support 35 the lading directly on the underframe by arranging the floor rack stringers, beams which support the floor, and underframe cross members substantially in a vertical plane, thereby transmitting the load directly to the underframe and relieving strain on other parts of the car. It is a further object of the invention to secure the floor rack stringers to the floor. They may then be made of thinner material and the dead weight 40 of the car decreased.

When a refrigerator car is engaged in a trip 45 lasting several days the roof of the car is alternately heated by the sun shining thereon and cooled by contact with the cool night air. Each 50 time the roof is cooled, the moisture in the air between the roof and ceiling is condensed and may leak through the roof and drip on the lading, thus damaging said lading. It is an object of this invention to provide a ceiling which will pre- 55

vent the condensed moisture from reaching the lading.

It is a further object of the invention to provide a ceiling to which the refrigerant containers may be easily attached.

It is another object of the invention to provide a ceiling having ribs projecting into the insulation thereabove to resist the tendency of the insulation to creep during the twisting and jolting which occurs during service movements of the car.

In the drawing:

Fig. 1 is a transverse section of a refrigerator car having a portion broken away; the left half being taken on line 1L—1L of Fig. 2 and the right half on line 1R—1R of Fig. 2.

Fig. 2 is a longitudinal section on line 2—2 of Fig. 1.

The underframe 2 of the car comprises a center sill 3 extending longitudinally of the car and cross members 4 which consist of bolsters, cross bearers and cross ties. The outer side sills 5 comprise channel shaped members 6 secured to the cross members 4 and angles 7 secured to the channels 6. Outer frame members 8 and sheathing 9 are secured to the side sills 5 and support the outer roof structure 10. The outer side plates 11 are secured to the frame members 8 and sheathing 9 at the top edge thereof. The roof 10 comprises a series of sheets 12 extending between the side plates 11, each of said sheets having an upwardly projecting central panel or corrugation 13 and upturned marginal flanges 14. The sheets 12 are secured together by inverted channel shaped seam caps 15 covering the flanges 14 and secured thereto. A sub-floor 16, made preferably of wood, to provide additional insulation, rests upon and is secured to the center sill 3, cross members 4 and outer side sills 5, thus forming a complete outer structure supported on the underframe 2.

A series of beams 25 rest upon the sub-floor 16 above the cross members 4 and support a floor 24. Inner side sills comprise angles 26 secured to the beams 25. The inner wall structure is formed by inner vertical frame members 27 and lining 28; the members 27 being secured to the inner side plate 29. The ceiling 30 extends between the side plates 29 and is supported thereon; the ceiling 30 comprising a plurality of transversely extending sheets 31 having upturned flanges 32 at the margins thereof. The flanges 32 project inside a plurality of inverted channel shaped seam caps 33 positioned above the ceiling 30. It is evident from the drawing that the inner structure comprising beams 25, wall 27—28 and ceiling 30 is supported directly on the underframe 2 of the car independently of the outer structure.

A plurality of refrigerant containers 40 having foraminous sides 41 and bottom 42 are positioned preferably in rows near the ceiling 30 and extend longitudinally of the car adjacent each lining 28. The containers 40 are suspended from the ceiling by elements 43 inserted between the upturned flanges 32 of adjacent sheets 31 and secured thereto by the rivets 44 which also secure the seam caps 33 to the ceiling sheets 31. Hatch frames 45 formed from metallic sheets extend from above the roof 10 to below the ceiling 30 and are positioned above the refrigerant containers 40. The hatches 46 are used to deposit refrigerant in the containers 40.

75 An insulated partition 50 is positioned below

each container 40 sloping slightly downwardly toward the side lining 28 to provide a passage 49 between the partition 50 and the container 40. An upright wall 51 projects upwardly from the partition 50 adjacent the center of the car. A plurality of vertical flues 52 formed preferably from thin metallic sheets 53 are between the sheathing 9 and lining 28, each flue 52 extending longitudinally of the car between the inner frame members 27 and being adjacent the lining 28. As a means for supporting the lading I have shown a floor rack 54 comprising a foraminous floor consisting of a flat perforated sheet 55 secured, preferably by welding, to a corrugated perforated sheet 56; the sheets 55—56 being spaced from the floor 24 by a plurality of transversely extending stringers 57. I have shown the stringers 57 as Z-bars positioned above and secured to the beams 25, thus supporting the lading directly on the beams 25 and cross members 4. Securing the stringers 57 by one flange thereof to the beams 25 makes it possible to form the stringers of thinner material than if the Z-bars were to rest unsecured upon the floor.

The refrigerant used in the type of car herein described is usually fresh water ice, ice mixed with salt to produce a lower temperature, or frozen brine, known as eutectic ice. The melted ice drips through the foraminous bottom 42 of the container, flows down the inclined partition 50 to the lower edge thereof, down the flues 52 to the floor 24 of the car, from which it drains into the gutters 65 and from the gutter to outside the car through water sealed drains provided for that purpose, but not shown on the drawing. The path of the air circulation is from the lading space 66 upwardly through the duct 67 formed by the upright walls 51, through the foraminous walls 41—42 of the container 40 where it is cooled by the refrigerant therein, downwardly through the flues 52 and into the space 68 under the floor rack 54. It is then free to rise from this space through the perforations in the sheets 55—56 absorbing heat from the lading as it rises toward the duct 67 to repeat the cycle.

The insulation 70, shown on the drawing, substantially fills the space between the outer structure which comprises sub-floor 16, sheathing 9 and roof 10 and the inner structure which comprises floor 24, lining 28 and ceiling 30. The inner and outer structures are spaced apart at all points except at the beams 25 which are the only means of support between the inner and outer structures, therefore, the car may be very efficiently insulated.

The flues 52 are positioned adjacent the lining and extend substantially between the vertical frame members 27. This is indicated by the dotted lines and arrows in Fig. 2. In Fig. 1 of Fig. 2, the left half of the section is on line 1A—1A of Fig. 2, showing the construction through the flue 52, while the right half of Fig. 1, on line 1B—1B of Fig. 2, shows the construction through a post 27.

The gutter 65 disclosed in this application is disclosed and claimed in my co-pending application Serial No. 213,089, filed June 10, 1938, and the side wall flue 52 shown herein is claimed in my co-pending application Serial No. 213,090, filed June 10, 1938.

The accompanying drawing illustrates the preferred form of the invention, though it is to be understood that the invention is not limited to the exact details of construction shown and

described, as it is obvious that various modifications thereof, within the scope of the claims, will occur to persons skilled in the art.

I claim:

secured in an upstanding position to said sills, lining secured to said frame members substantially in contact therewith, outer sheathing spaced outwardly from said frame members, means to 5 secure the sheathing to said underframe parts independently of said sills, an outer roof extending between the sheathing on opposite sides of the car, a ceiling supported by said frame members in spaced relation to said roof, insulation between 10 said sheathing and said lining and between said roof and said ceiling, spaced apart carlines extending across the car, means associated with the upper parts of said inner frame members to support said carlines, and refrigerant containers 15 spaced apart at the center of the car and supported by said carlines.

7. In a refrigerator car having an underframe comprising spaced apart transversely disposed parts extending substantially between opposite 20 side margins of the car, a sub-floor supported by said parts, spaced apart members above said sub-floor arranged to be each supported solely by one

of said underframe parts, a main floor supported by said members, inner side sills supported by said members above said main floor and adjacent the outer ends of said underframe parts, insulation between said main floor and sub-floor, inner frame members secured in an upstanding position to said sills, lining secured to said frame members substantially in contact therewith, outer sheathing spaced outwardly from said frame members, means to secure the sheathing to said 10 underframe parts independently of said sills, an outer roof extending between the sheathing on opposite sides of the car, a ceiling supported by said frame members in spaced relation to said roof, insulation between said sheathing and said 15 lining and between said roof and said ceiling, spaced apart carlines extending across the car, means associated with the upper parts of said inner frame members to support said carlines, and refrigerant containers supported by said car- 20 lines.

VICTOR E. WEST.
